Primary Examiner — Mary Ann Calabrese

Assistant Examiner — Catherine Ho

(57) **CLAIM**

I claim the ornamental design for a music stand tray extension, as shown and described.

DESCRIPTION

FIG. 1 is a front view of a music stand tray extension, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is a perspective view of a music stand tray extension shown in an environment of use.

The broken line portion of the figure drawings is included to show environment that forms no part of the claimed design.
